UNITED STATES PATENT OFFICE.

ROBERT B. PUCKETT AND HARRY R. ABBOTT, OF ST. LOUIS, MISSOURI.

APPARATUS FOR USE IN OPERATING UPON SHOE-SOLES.

1,254,010.

Specification of Letters Patent. Patented Jan. 15, 1918.

Application filed April 27, 1916, Serial No. 93,893. Renewed June 8, 1917. Serial No. 173,649.

To all whom it may concern:

Be it known that we, ROBERT B. PUCKETT and HARRY R. ABBOTT, citizens of the United States, residing in the city of St. Louis and 5 State of Missouri, have invented new and useful Improvements in Apparatus for Use in Operating Upon Shoe-Soles, of which the following is a specification.

This invention relates to the art of manufacturing shoes, and has special reference to a novel apparatus for enabling a lift to be cut from the heel-seat portion of the outer sole after the tread portion of the latter has been secured to the upper. The objects of 10 the invention are to provide means for enabling a lift to be cut from the heel-seat portion of the outer sole of a shoe without danger of injuring or cutting the part of the shoe beneath the sole; to provide in such an apparatus means for enabling the heel-seat portion of the sole to be accurately positioned with reference to the cutting implement, or die, so that the opening made in the sole by cutting the lift therefrom will be 15 correctly centered with respect to the heel-seat portion of the sole and the heel to be applied thereto; and, finally, to provide adjusting means for enabling the device to accommodate shoes of different size.

20 In the manufacture of shoes as now practised, the outer sole, consisting of an integral piece of leather, is secured to the upper and then the heel secured to the heel-seat portion of the sole. The heel-seat portion 25 of the sole is never subjected to any wear, and it has heretofore been proposed to remove a portion of this leather in the shape of a lift which may be used as the top lift for a heel, and thereby secure great economy 30 in the manufacture of shoes. In attempting to do this the lift has been cut from the heel-seat portion of the outer sole, and a filling tenon of approximately the size of the lift cut, and of cheaper material, has been 35 secured to the heel and then the heel applied in position in the usual way after the sole has been secured to the shoe, so that the tenon will fill the space made by removing the lift. It was soon discovered that this 40 was an impracticable method of procedure, owing to the impossibility of properly positioning the recess in the sole with respect to the tenon on the heel, so that when the heel was applied it would be exactly centered 45 with respect to the sole.

In a companion application of the present

inventors, filed January 12th, 1916, Ser. No. 71,619, it has been proposed to cut the lift from the sole after the tread portion of the sole has been sewed to the upper, and before 50 the heel-seat portion has been nailed thereto. In carrying out this idea it was thought possible to cut the lift from the sole by the use of a reciprocating die while the last was yet in the upper, thus utilizing the last to 55 offer the necessary resistance to the die to enable the latter to cut through the sole. It was found, however, that the ordinary lasts used are not uniform in size, even for the same style of shoe, and that frequently the 60 die would cut through the outer sole and into the inner sole, and such method of procedure was found impracticable.

The present invention enables the above objections to be overcome and permits the 65 lift to be cut from the sole in a simple, efficient and economical manner, as will hereinafter be described.

Referring now to the drawing—

Figure 1 is a plan view showing a shoe 70 with the outer sole secured thereto, and in position on a novel support permitting a lift to be cut from the heel-seat portion without the danger of cutting any other portion of the shoe, the view showing the sole with 75 the cut lift removed;

Fig. 2 is a view in side elevation, showing a shoe in position on the improved support, and illustrating conventionally a die for cutting the lift from the heel-seat portion of 80 the sole;

Fig. 3 is a view in front elevation of the improved support; and

Fig. 4 is a sectional view of a heel supplied with a tenon for filling the opening 85 made by removing the lift from the outer sole.

The numeral 1 indicates a support, such as a table, or the like, on which is mounted a head 2 having yoke-members 3, which are 90 connected at their upper end by a block 4, which is preferably cast integral with the yoke-members 3. The block 4 is flat on its upper side, and has a rounded end portion 5 projecting slightly beyond the front side of 95 the yoke-members 3, and its under side is inclined rearwardly from said front end to the end of an extension 6 which projects a considerable distance beyond the rear sides of the yoke-members 3. The extension 6 is 100 in the form of a plate, and at the point where it projects from the block 4 the latter

provides a vertically-disposed shoulder 7. Secured on the upper side of the block 4 is a flat, metal plate 8 which at its rear side is bent at right angles to itself, as indicated at 5 9, to extend over the shoulder 7, to which it is secured by means of screws 10. The under side of the block 4 and of the plate 6 form one continuous inclined surface, as shown more clearly in Figs. 2 and 3, and indicated by the numeral 11. The numeral 10 12 indicates a gage-plate which is cut away to provide a V-shaped recess from the edges of which depend guide-members 13 formed integral with said plate and converging 15 from the forward edge and outer side thereof to a point about midway of the plate. Toward its outer end the plate 12 is provided with slots 14 which are adapted to loosely receive the screw-threaded ends of 20 set screws 15 which pass through apertures 16 formed in the rear end of the plate 6, the screw-threaded ends of said screws being received in screw-threaded apertures formed in the outer end of a nut plate 17.

25 In proceeding according to the present invention, an outer sole 18 is stitched to the upper in the usual way, as indicated by the row of stitching 19, leaving a heel-seat portion 20 free, that is, unconnected with the 30 upper. The operator places this heel-seat portion on the plate 8 and places the shoe between the yoke-members 3, its heel-portion engaging the inclined side 11 of the block 4, and being guided to a true central 35 position by the guide-members 13, which also act to limit the inward movement of the shoe. A die 21, which is shown removably secured in a holder 22, is then reciprocated in a defined path, as by a plunger 22^a, 40 in any preferred way to cut a lift from the heel-seat portion 20, in which operation the cutting edge of the die will pass through the outer sole and engage the plate 8 which is preferably of soft metal. The cutting of the 45 lift provides an opening 23 in the heel-seat portion of the sole, which is correctly positioned with reference to the heel portion of the shoe. When the shoe is removed from the block 4 the lift is carried with it and is 50 then easily removed by hand. The heel-seat portion of the outer sole is then nailed to the counter and inner sole of the upper in the usual way, after which a heel 24, provided with a tenon 25, is applied to the outer 55 sole, the tenon filling the opening 23 made by removing the lift from the sole. By loosening the set screws 15 it is obvious that the gage-plate 12 may be adjusted to permit the guide-members 13 to properly position varying sizes of shoes.

60 From all of the foregoing it will be readily appreciated by those skilled in the art that by the use of the apparatus herein described a lift may be cut from an outer sole in such manner that when the heel hav-

ing a filling tenon thereon is applied to the sole the heel will be correctly positioned or centered with respect to the latter.

It is contemplated that the plunger 22^a will form part of a suitable machine whereby the die 21 may be given a single reciprocation at the will of the operator for cutting the lift when successive shoes have been adjusted to the proper position on the support. Such machine, however, forms no part of 75 the present invention, and we have merely shown, more or less conventionally, a guide 26 in which the plunger 22^a reciprocates, and which causes the same to move in a defined path with respect to the plate 8 on the 80 block 4.

We claim:

1. An apparatus of the character described, comprising a sole support adapted for insertion between the heel seat portion 85 of the sole and a corresponding portion of the upper and when so positioned to extend under and to support the entire heel seat portion of the sole, and a lift-cutting die supported in opposed relation to said member and positioned to operate within the confines of the supported heel seat portion, the sole support and lift-cutting die being constructed and arranged to enable relative movement therebetween effective to bring 95 them into contact.

2. An apparatus of the character described comprising a sole support adapted for insertion between the heel-seat portion of the sole and a corresponding portion of the upper, and when so positioned to extend under and to support the entire heel-seat portion of the sole, and a lift-cutting die mounted to be moved in a right line toward 100 and from said member and positioned to 105 operate within the confines of the supported heel-seat portion.

3. An apparatus of the character described comprising a supported member having a tapered portion presenting a flat 110 upper side and an inclined under side converging to the front edge of said upper side, said tapered portion being insertible between the unattached heel-seat portion of a sole and a corresponding portion of an upper, 115 and means for positioning a shoe on and in fixed relation to said apparatus with the heel-seat portion of the sole extending entirely over and supported on said flat upper side.

4. An apparatus of the character described comprising a supported member adapted for insertion between the heel-seat portion of a sole and a corresponding portion of the upper and having a flat upper side and an inclined under side converging toward the front edge of said upper side, said flat and inclined sides being of an extent in operation to pass entirely within the space between the said heel-seat portion of 125 130

the sole and the corresponding portion of the upper, and guides positioned on the under side of said member and converging rearwardly with respect thereto.

5. An apparatus of the character described comprising a supported member having a flat upper side and an inclined under side converging toward the front edge of said upper side, and a plate adjustably supported on the under side of said member and carrying guide members converging rearwardly with respect thereto.
10. An apparatus of the character described comprising a supported member having a flat upper side and an inclined under side converging toward the front edge of said upper side, and a plate adjustably supported on the under side of said member and carrying guide members converging rearwardly with respect thereto.

15. An apparatus of the character described comprising a supported member having a flat upper side and an inclined under side converging toward the front edge of said upper side, a plate adjustably supported on the under side of said member and having a V-shaped recess in its forward side, and guide members depending from the edges of said recess.

20. An apparatus of the character described comprising a stationary yoke, a block supported between the legs thereof at one end of the yoke and having a tapered portion presenting a flat upper side and an inclined lower side converging toward the forward edge of said upper side, said tapered portion being adapted for insertion between the unattached heel-seat portion of

a sole and the corresponding portion of an upper, and when in said position to support said heel-seat portion of the sole on its upper flat side, and a guide member mounted on the under side of said block to the rear 35 of its forward edge portion and adapted to be engaged by the heel portion of the upper to limit the extent of insertion of said tapered portion and to position said heel-seat portion of the sole upon the upper flat side 40 of said block.

8. In a device of the character described, a stationary yoke, the arms whereof are spaced a sufficient distance apart to permit the entrance of the heel portion of a 45 shoe-upper between them, and a wedge shaped block mounted at one end of said yoke and extending between the arms thereof and affording an upper flat side, said flat sided portion being of an extent to be 50 passed between the unattached heel-seat portion of a sole and the corresponding portion of an upper and to support the central area of said heel-seat portion upon its flat upper side.

55
In testimony whereof, we have hereunto set our hands.

ROBERT B. PUCKETT.
HARRY R. ABBOTT.
